UNITED STATES PATENT OFFICE.

WILLIAM MARSHALL, OF DETROIT, MICHIGAN, ASSIGNOR TO BRIGGS MANUFACTURING COMPANY, OF DETROIT, MICHIGAN, A CORPORATION OF MICHIGAN.

PLIERS.

Application filed August 25, 1924. Serial No. 734,125.

This invention relates generally to tools designed for connecting sheet metal parts such as the panels of vehicle bodies and consists of certain novel features of construction and combination of parts as hereinafter set forth.

In the accompanying drawings:

Figure 1 is a side elevation of a tool embodying my invention applied to the flanges 10 of adjacent sheet metal panels of a vehicle body;

Figure 2 is a fragmentary elevation of the tool applied to the flanges and showing the position of the lever after a tongue has been 15 struck out from the uppermost flange;

Figure 3 is a view similar to Figure 2 but showing the position of the lever after the struck-out tongue has been bent against the lower-most flange to provide a finished 20 joint;

Figure 4 is a detail elevation of the lever;

Figure 5 is a detail elevation of the lower handle;

Figure 6 is a top plan view of the lower 25 handle;

Figure 7 is a detail elevation of the upper handle;

Figure 8 is a top plan view of the upper handle.

Referring now to the drawings in which like characters of reference designate corresponding parts throughout the several views, the numerals 1 and 2 respectively designate sheet metal panels that are preferably secured to a suitable frame (not shown) of a vehicle body. For effecting a joint between the panels at the adjacent edges thereof, the lower panel 2 is preferably formed with an outwardly embossed portion 3 that connects 35 into an inwardly extending flange 4, while the upper panel 1 is preferably embossed outwardly to provide a strip of molding 5 for overlapping the embossed portion 3 of the lower panel and is provided at the free 40 edge of the molding with a close return-bent portion 6 that engages the curved inner face of the molding and connects into an inwardly extending flange 7. This flange preferably projects slightly beyond the inner edges 45 of the flange 4 and is adapted to be cut at spaced points by means of a pair of pliers 8 to provide a plurality of tongues 9. These 50 tongues are subsequently bent by the pliers over and against the flange 4 for holding 55 the embossed portion 3 in firm engagement

with the return-bent portion 6 to secure the panels together. The pliers 8 preferably comprise a pair of handles 10 and 11 respectively having bifurcated end portions 12 and 13 pivoted upon a suitable bolt 14. 60 The furcations of the handle 11 preferably terminate in spaced jaws 15 having serrated faces 16 while the furcations of the handle 10 are preferably connected at their ends by a jaw 17 that is also provided with a serrated face 18 and is adapted to cooperate with the jaws 15 to clamp the flanges 4 and 7 together.

In order that the tongues 9 may be struck out from the flange 7 and subsequently bent over and against the flange 4 by means of the same tool, I preferably provide a lever 19 that is pivoted upon the bolt 14 between the furcations of the handle 11 and that is provided beyond the pivot bolt 14 with the 70 spaced projections 20 and 21 respectively. The projection 20 is preferably provided with shearing edges 22 which are adapted to cut out the tongues 9 when the lever 19 is moved upwardly in the direction of the arrow shown in Figure 2 of the drawing and is provided with a forwardly inclined end portion 23 for pressing these tongues downwardly to the position shown in Figure 2 of the drawing after they are cut. The projection 21 is preferably longer than the projection 20 and is provided with a flat 75 face 24 that is adapted to move upwardly between the spaced jaws 15 when the lever is moved downwardly, as shown by the arrow 80 in Figure 3 of the drawing, for pressing the tongues upwardly against the lower face of the flange 4 to provide a finished joint.

For normally holding the lever 19 in spaced relation to the handles 10 and 11 so that it will not interfere with the use of the handles, I preferably provide a coil spring 25 that is terminally connected to a screw 26 threadedly engaging the lever 19 and to a clip 27 mounted on the bolt 14. 85

From the foregoing description, it will be readily apparent that I have provided a very practical pair of pliers that is equipped with means for moving the flanges of the panels in opposite directions so that the adjacent edges of the panels will be drawn together to form a tight joint and for subsequently holding these flanges together while the tongues are cut from one flange 105 and subsequently bent over and against the 110

other flange. Thus, I have provided a very simple tool that may be readily used by any unskilled person for properly uniting adjacent panels of a vehicle body.

5. While it is believed that from the foregoing description, the nature and advantages of the invention will be readily apparent, I desire to have it understood that I do not limit myself to what is herein shown and described, and that such changes may be resorted to when desired as fall within the scope of what is claimed.

What I claim as my invention is:

1. A tool of the class described comprising a pair of handles, a pivot therefor, jaws carried by said handles, and a lever mounted on said pivot and having spaced projections, one of said projections having shearing edges for cutting a tongue from a sheet of metal, 20 the other projection having a bearing face for bending said tongue.

2. A tool for securing together adjacent sheet metal panels having substantially parallel flanges comprising clamping jaws engageable with the flanges for drawing the adjacent ends of the panels together, handles for operating said jaws, and a lever having means for cutting a tongue from one flange and bending the tongue out of the plane 30 of the flange, said lever also having means for subsequently bending the tongue over and against the other flange for holding the adjacent ends of the panels together.

3. A tool for securing together adjacent sheet metal panels having substantially parallel flanges comprising clamping jaws engageable with the flanges for drawing the adjacent ends of the panels together, handles for operating said jaws, and a lever having 40 spaced projections, one projection having shearing edges for cutting a tongue from one of the flanges aforesaid and bending the tongue out of the plane of said flange the other projection having a flat face engageable with the tongue for bending the same over and against the other flange aforesaid to hold the adjacent ends of the panels together.

4. A tool for connecting together sheet metal parts, having cooperating jaws for holding said parts, and a lever connected to the jaws having means for cutting a tongue from one of said parts, and means for bending the tongue over the other of said parts.

5. A tool for connecting together sheet metal parts, having cooperating jaws for holding the said parts, levers for actuating said jaws, and a third lever having means for cutting a tongue from one of said parts, and a projection for bending the tongue over the other of said parts.

6. A tool for connecting together sheet metal parts, having cooperating jaws for holding the parts, levers for actuating said jaws, a third lever having a projection for

cutting a tongue from one of said parts, and a projection for bending the tongue over the other of said parts, and means normally holding the third lever in spaced relation to the first mentioned levers.

7. A tool for connecting together sheet metal parts, having cooperating jaws for holding said parts, levers for actuating said jaws, a third lever having means for cutting a tongue from one of said parts, and means for bending the tongue over the other of said parts, and a common pivot for all of said levers.

8. A tool for connecting together sheet metal parts, having cooperating jaws for holding the said parts, levers for actuating the jaws, a third lever having a projection for cutting a tongue from one of said parts and a second projection for bending the tongue over the other of said parts, a pivot for said levers, a clip on the pivot, and a yieldable member connected to the clip normally holding the last mentioned lever in spaced relation to the first two mentioned levers.

9. A tool for connecting adjacent flanges of sheet metal panels comprising a pair of handles having bifurcated end portions, the bifurcated end portion of one handle extending between the furcations of the other handle, spaced jaws projecting from the furcations of one handle, a cooperating jaw connecting the furcations of the other handle, a pivot for said handles, a lever mounted on said pivot having means for cutting a tongue from one of said flanges, and means for bending the tongue over the other of said flanges.

10. A tool for connecting together sheet metal parts comprising a pair of handles having bifurcated end portions, cooperating jaws associated with said handles for holding said parts, and a lever disposed between the furcations of said handles having spaced projections, one of said projections provided with means for cutting a tongue from one of said parts and the other projection provided with means for subsequently bending the tongue over and against the other of said parts.

11. A tool for connecting together sheet metal parts, having cooperating jaws for holding the parts, a lever disposed between said jaw members having a projection for cutting a tongue from one of said parts, and a second projection on said lever having a bearing surface for bending the tongue over the other of said parts.

12. A tool for connecting together sheet metal parts comprising a jaw member, a cooperating jaw member straddling the jaw member aforesaid, a lever disposed between the jaw members, a common pivot for said jaw members and lever, and means formed on said lever for cutting a tongue from one

of said parts and bending the tongue out of the plane of said part.

13. A tool for connecting together sheet metal parts comprising a jaw member, a second jaw member pivotally mounted on and cooperating with the jaw member aforesaid for holding said parts, and a lever movable between portions of one of said jaw members for cutting a tongue from one of 10 said parts.

14. A tool for connecting together adjacent flanges of sheet metal panels, having means for holding the flanges, a lever pivotally connected to said holding means, and means integral with said lever for cutting a tongue from one flange and subsequently bending the tongue over the other flange. 15

In testimony whereof I affix my signature.

WILLIAM MARSHALL.
